HOSE NOZZLE

Robert A. Gilmour, ½ Gilmour Manufacturing Co.,
Somerset, Pa.

Filed Jan. 21, 1965, Ser. No. 83,509

Term of patent 14 years

(Cl. D91—1)

FIGURE 1 is a perspective view of a hose nozzle showing my new design;

FIGURE 2 is a front end view thereof;

FIGURE 3 is a rear end view thereof;

FIGURE 4 is a bottom elevational view thereof; and

FIGURE 5 is a side elevational view thereof.

The dominant features of my design reside in the portions shown in solid lines.

I claim:

The ornamental design for a hose nozzle, as shown and described.
